UNITED STATES PATENT OFFICE.

JOHN S. BAKER, OF LOS ANGELES, CALIFORNIA, ASSIGNOR, BY MESNE ASSIGNMENTS, TO ANDERSON-BARNGROVER MFG. CO., OF SAN JOSE, CALIFORNIA, A CORPORATION OF CALIFORNIA.

CAN-COOKING MACHINE.

1,315,073.

Specification of Letters Patent.

Patented Sept. 2, 1919.

Application filed July 12, 1916. Serial No. 108,827.

To all whom it may concern:

Be it known that I, JOHN S. BAKER, a citizen of the United States, residing at Los Angeles, in the county of Los Angeles and State of California, have invented certain new and useful Improvements in Can-Cooking Machines; and I hereby declare that the following is a full, clear, and exact description thereof, reference being had to the accompanying drawings, which form part of this specification.

The present invention relates to apparatus for cooking canned goods, of the general type disclosed in my Patents No. 1,182,832 of May 9, 1916 and No. 1,181,057 of April 25, 1916, and has for its purpose to provide an arrangement having adjustable means for selectively controlling at will the discharge of the cans after cooking, and in which said delivery control will effectively prevent the discharge of any other cans undergoing the cooking operation.

The invention has for its further purpose to provide a can cooking apparatus having a can feeding means and an adjustable can discharge means control located in a position whereby all work pertaining thereto may be performed by one operator; and in which the adjustable discharge means may be instantly operated to discharge the cans after the proper periods of cooking without requiring removal or replacement of any parts.

A further purpose of the invention consists in providing an apparatus of this character having a can way that is of combined spiral and zigzag formation to the end that the canned goods may be cooked at selective periods within a wider range of time than has heretofore been obtainable. And in having the apparatus equipped with a plurality of discharge means located at different points and under independent control in order that the cans may be delivered at any selected stage in their travel.

The invention is shown by way of illustration in the accompanying drawings wherein:

Figure 1 is a vertical longitudinal sectional view of the apparatus.

Fig. 2 is a top plan view of the same with the casing partly broken away.

Fig. 3 is an enlarged elevational view of a portion of one of the adjustable can discharge controlling devices.

Fig. 4 is a transverse sectional view of the same.

Fig. 5 is a detail sectional view of the adjustable discharge controlling slide.

Fig. 6 is a detail sectional view of a form of feed employed for high pressure tanks; and

Fig. 7 is a detail sectional view of the discharging apparatus therefor.

Referring to the construction in further detail, the apparatus consists of a casing 1 adapted to contain heated water, steam or hot air for heating purposes and adapted to inclose mechanism for advancing cans and directing them in their movement back and forth until the materials therein have been properly cooked. The said casing or tank is preferably made of sheet metal of any desired or necessary thickness and is suitably supported. A plurality of coils of piping 2 and 3 for the heating medium is mounted in the casing on a suitable frame work of T-bar construction, which also serves to support the can way and the conveyer apparatus to be described.

The can way comprises track sections 5, 6 and 7 that are arranged in a continuous spiral formation substantially as shown in my patents above referred to, though in the present instance the track sections 7 are arranged in superposed stages after the manner illustrated in Fig. 1. A plurality of fillers or bars 8 (see Fig. 2) is disposed between the tracks of the respective ways to keep the traveling cans in their properly spaced relation and to guide the same throughout the successive convolutions of the spiral can ways as will be understood.

The superposed stages 7 of the can way have the respective track lengths thereof connected within the casing by curved track portions 9 and at their outer ends the casing wall 10 is curved at 11, symmetrically with the portions 9, and each of said curved portions has the inner track part 12 mounted for adjustment to the end that the curved portions on the can way may be regulated to provide a continuous passage in accordance with the diameters of the cans to be passed therethrough. Each track portion 12 is flexible and mounted on the stud 13 to be flexed by a manually operated bar 14 that is fitted with a handle 15 located on the outside of the tank or casing. The two

lower bars 14 at the rear of the tank engage respectively with a pair of levers 16 and 17 suitably fulcrumed on the can way and oppositely acting to the end that two 5 of the track sections 12 may be adjusted by one and the same operation. The said levers 16 and 17 are connected to their respective track sections by rods 18 and 19 or any other preferred manner. The track adjusting bars 10 14 at the top and rear of the casing are connected each to a single lever 20, likewise fulcrumed at 21 on the can way and connected by the rod 22 with the related section 12 as shown. Similar adjustable track 15 sections 23 are located at the lower and forward end of the tank just in advance of the can feeding point, and said parts are each operated by a rod 14 through the bell crank lever 24 whose arms engage respectively with said rod 14 and the rod 19 that engages the member 23. It will therefore be 20 seen from the foregoing that the several sections or convolutions of the spiral can way may be adjusted in accordance with the size of the cans to be used and all in a 25 convenient manner from positions within easy reach of the operator. It will be further noted that the series of controlling devices located at the front of the machine 30 may be worked by the operator without requiring his leaving that position where he controls both the feeding of the cans into the cooker and the delivery of the discharged cans. The track sections are so 35 connected that they form, as in my said patents, one continuous irregular spiral can-way having a plurality of parallel convolutions or runs each extending throughout the length of the several sections, and the 40 end of one run of the can-way merging into the beginning of the next succeeding run.

The conveying apparatus consists of a pair of chains 25 disposed on either side of the machine and mounted to travel on the series of sprocket wheels 26, 27, 28 and 29 that are mounted on the shafts 30. The driving sprockets are adapted to be connected with any suitable transmission and the conveyer chains 25 are connected at suitable intervals by the transverse slats 31 usually employed for moving the cans.

A feeding hopper 32^a is mounted on the casing at one side (see Fig. 2) to position the cans on the first upwardly moving flight 55 and it is arranged that the cans be discharged at periods in their travel commensurate with the time they are subjected to cooking. The several discharging devices employed are independently controllable to 60 the end that the cans may be delivered from the cooker at any selected flight of the can way.

The discharging apparatus are distributed one at the front part of the cooker and 65 a series at the rear thereof in the manner

shown in Fig. 1. Each of said discharging devices consists of a pair of flanged members 32 and 33 forming guides that receive the slide or closure 34 that is formed with an opening 35 therein adapted to register 70 selectively with any selected flight of the spiral can way and allow the cans thereof to be discharged by gravity after the manner illustrated in Fig. 1. Said slide 34 is curved concentric with the adjacent part of 75 the wall and provides therewith a part of the can way to guide the moving cans when the discharge outlet is out of register.

The adjustable slides 34 are each adapted to be manually operated by a hand wheel 80 36 journaled in suitable bearings 37 on the casing and having a pinion 38 that engages with a rack bar 39 carried by the slide after the manner shown in Figs. 4 and 5. And said wheel is adapted to be locked in said 85 position for holding the discharge opening 35 to receive the cans by a pin 40 passing through said wheel 36 and engaging in the aperture of an arm 41 mounted on the 90 casing.

It will be noted that the adjustable discharge controlling slide or closure has the opening 35 therein just large enough to allow one can to pass, and there is therefore no possibility of the cans being discharged 95 from the can ways otherwise. The slide may be set instantly, as there is no part to be removed, opened or closed which would cause confusion to the operator when working. The discharge port may be properly 100 located when the machine is full of cans, as the operator can always look in the port and see the cans passing same, and at the proper time, he can instantly throw the slide to bring the port in front of the can, 105 and in fact he may, when ready to make a quick change, first shift the slide so as to bring the port partly over the run of the can way where the cans are passing and then when it is desired to throw open the 110 port, the slide may be moved the balance of the way to register with the run of the can way. And in addition to seeing the cans the operator would know which can to let 115 discharge and which to allow to pass.

In this connection, it may be stated that in cooking different fruits there may be one lot of cans containing goods requiring a three-minute cook, another lot a five-minute cook, and a further lot a ten-minute cook 120 and so on. The three-minute cook would be placed in the machine first and behind this would be placed a pilot can of conspicuous color (e. g., black), then after a space of several feet would come the cans containing goods to be cooked five minutes, also with a pilot can following of another color (e. g., red). The operator would set the discharge port to first take off the cans of the three-minute 125 cook, and as soon as the pilot can appeared 130

he would shift it along to conform with the five minute run of the can-way, and as soon as these cans were discharged the slide would be shifted over to conform with the ten minute run of the can-way. Now, supposing there followed the ten-minute cook cans a lot to be cooked about seven minutes: In this event the operator would shift the slide back, and by looking in the port would see when 10 the cans had arrived at the seven minute run of the can-way, and if so, the slide would be set for the next succeeding runway, which would overcook them a little, but would not result in clogging the machine.

15 An apparatus for mechanically feeding the cans to the cooker as illustrated in Fig. 6 may be employed when the cooker is to be operated under high temperature. Said apparatus consists of a rotary valve 42 mounted in a cylindrical casing 43 which is formed with a discharging neck or throat 44 adapted to deliver cans into the hopper opening. The rotary valve 42 is constructed with a pair of opposed pockets or chambers 20 45 adapted to receive the cans and discharge them into the feed opening in the valve casing, and which cans may be fed to the valve by an endless conveyer 47 that operates to feed the cans along tracks 48 disposed in 25 feeding relation to said valve. With this construction it will be observed that the steam or other heating medium cannot escape from the heating chamber, and that the cans may be fed to the can way in 30 regular order.

It will be understood that more than one mechanical feeding apparatus may be employed for delivering to the cooker different lots of canned goods that are to receive cooks 40 of different periods, so that if desired a plurality of series of cans of the same or different size, whose contents require different times for cooking, may be passed through the machine at the same time, which 45 can be readily done by properly adjusting the feeding and the discharging devices. Suitable conveyers may be provided as described in my said patent to receive the goods discharged from the chamber through 50 any of the outlets and carry same to a point of further disposition.

When the feeding apparatus disclosed in Fig. 6 is employed a mechanically operated receiver for the cooked cans is preferably used in conjunction therewith; *i. e.*, when the machine is operating under high temperature. This apparatus is disclosed in Fig. 7 and consists of a casing or tank 49 having a partition 50 dividing the same into a hot water chamber 51 and a cold water chamber 52, and so located that the hot water chamber receives the discharged and cooked cans from the chute 53 whose delivery end is submerged below the surface

of the water to form a water-seal for the 65 heater and thereby prevent the escape of the heating medium. A conveyer chain 54 is mounted to travel in the tank 49 on the sprockets 55 and 56 located at the respective ends thereof and co-operates with suitable 70 tracks 54^a that support the cans. The tracks have elevated portions between the chambers 51 and 52 rising above the liquid level and a pair of sprockets 57 is located just 75 over the partition for transferring cans from the hot water chamber 51, past said partition and into the cold water chamber 52. A hood or "goose-neck" 58 is suitably mounted on the casing and overlies the raised portion of the conveyer in the manner shown. And the 80 respective ends 59 and 60 of the hood are submerged below the water level to form a liquid seal and thereby not expose the cans to the chilling influence of the atmosphere as they are transferred from the chamber 51 85 into the chamber 52.

In operation the cans are deposited on the tracks 54^a and carried by the chains 54 up over the "goose-neck" out of the water but do not strike the atmospheric air which is 90 excluded by the hood 58. The cans are then delivered into the cold water tank 52 and thence carried from the same and cooled before striking the air when they are discharged at the back by the raised track portion 61. When the apparatus disclosed herein is employed it is proposed to seal the several controlling slides of the cooker not in use with suitable packings for the purpose of avoiding the escape of steam or other 95 heating medium.

It is obvious that those skilled in the art may vary the details of construction and arrangement of parts without departing from the spirit of my invention, and therefore I do not wish to be limited to such features except as may be required by the 100 claims.

What I claim is:

1. In a cooking apparatus the combination 110 of a casing providing a cooking chamber, a can way located in said chamber and arranged in spiral and superposed stages, discharge outlets for the cans located at the respective stages of the rear of the casing, and a discharge outlet located at the front of the casing.

2. In a cooking apparatus the combination 115 of a casing providing a cooking chamber, a can way located in said chamber and arranged in zig-zag formation therein, means for moving the cans on said can way, and a closure adjustably mounted on the casing having an opening adapted to register with any run of the can way.

3. In a cooking apparatus the combination 120 of a casing providing a cooking chamber, a can way located in said chamber and

arranged in superposed zig-zag formation therein, means for moving the cans on said can way; and a closure adjustably mounted on the casing having an opening adapted to 5 register with any run of the can way.

4. In a cooking apparatus the combination of a casing providing a cooking chamber, a can way located in said chamber and arranged in spiral and zig-zag formation 10 therein, means for moving the cans on said 15 way; and a closure adjustably mounted on the casing having an opening adapted to register with any run of the can way.

5. In a cooking apparatus the combination of a casing providing a cooking chamber, a can way located in said chamber and arranged in spiral, superposed zig-zag formation 20 therein, means for moving the cans on said can way; and a closure adjustably mounted on the casing having an opening adapted to 25 register with any run of the can way.

6. In a cooking apparatus the combination of a casing providing a cooking chamber, a can way located in said chamber and arranged in spiral and superposed stages, and discharge outlets for the cans located at 30 the respective stages; and a plurality of closures located at different points and adjustable, each closure having an opening adapted to register with an opening in

different runs of the can way for discharging cans therefrom.

7. In a cooking apparatus the combination of a casing providing a cooking chamber 35 having a plurality of openings therein, a spiral can way located in said chamber and arranged in zig-zag formation, means for moving the cans on said can way, and an adjustable closure having a can discharge 40 opening mounted on the casing at each of said openings.

8. In a cooking apparatus the combination of a casing providing a cooking chamber, a spiral can way therein having opposite 45 bends and an adjustable section at each bend, means connecting said opposite adjustable sections, and means for simultaneously adjusting said opposite sections.

9. In a cooking apparatus the combination of a casing providing a cooking chamber, a spiral can way therein having superposed stages with opposite curved portions 50 at the ends of such stages, adjustable sections connected to said curved portions, rods connecting said sections for simultaneously shifting them, oppositely acting levers fulcrumed on the casing and connected to said rods, and means for actuating said levers.

In testimony that I claim the foregoing 60 as my own, I affix my signature.

JOHN S. BAKER.
